US0D1096156S

(12) **United States Design Patent** (10) **Patent No.:** **US D1,096,156 S**
(45) **Date of Patent:** **** Oct. 7, 2025**

(54) **HARDWIRE KIT ORGANIZER**

(71) Applicant: **Hangzhou Tanlink Technology Co., Ltd.**, Hangzhou (CN)

(72) Inventor: **Junjun Tang**, Hangzhou (CN)

(73) Assignee: **Hangzhou Tanlink Technology Co., Ltd** (CN)

(**) Term: **15 Years**

(21) Appl. No.: **29/946,433**

(22) Filed: **Jun. 7, 2024**

(51) LOC (15) Cl. **03-01**

(52) U.S. Cl.

USPC **D3/273; D3/294**

(58) **Field of Classification Search**
